[57] CLAIM

The ornamental design for a waffle iron, as shown and described.

DESCRIPTION

FIG. 1 is a top, front and side perspective view of a waffle iron showing my new design;

FIG. 2 is a side elevational view thereof;

FIG. 3 is a side elevational view thereof from the side opposite that shown in FIG. 2;

FIG. 4 is a rear elevational view thereof;

FIG. 5 is a top plan view thereof;

FIG. 6 is a bottom plan view thereof; and,

FIG. 7 is a view similar to FIG. 1 but showing the waffle iron in an open position.
